ESTHER BORGENICHT, OF NEW YORK, N. Y., ASSIGNOR TO BRAND BROTHERS, OF NEW YORK, N. Y., A FIRM COMPOSED OF ABRAHAM BRAND AND LOUIS BRAND.

GARMENT.

Specification of Letters Patent. Patented Feb. 21, 1922.

Application filed June 11, 1921. Serial No. 476,846.

To all whom it may concern:

Be it known that I, ESTHER BORGENICHT, an Austrian subject, and resident of the city, county, and State of New York, have 5 invented a certain new and useful Improvement in Garments, of which the following is a specification.

This invention relates to a garment particularly adapted to be worn by children and 10 which is in the nature of a combination garment comprising a body portion having a combined skirt and trousers portion, said parts being united to form a single unitary garment which may be readily placed on the 15 wearer and removed therefrom and which may be worn with comfort and convenience.

With these objects and other objects which may hereinafter appear in view, I have devised the particular arrangement of parts 20 hereinafter set forth and more particularly pointed out in the claims appended hereto.

Reference is to be had to the accompanying drawings, forming a part hereof in which—

25 Figure 1 is a rear elevation of the garment, parts being broken away to disclose construction.

Throughout the various views of the 35 drawings, similar reference characters, designate similar parts.

In the preferred embodiment of my invention, 1 indicates the waist portion or body of the garment which may be of any suitable design and may be provided with attached sleeves 2. The body portion 1 of the garment is provided with a rear opening 3 adapted to be closed by means of buttons 40 engaging with the button holes or other suitable closure means may be used. The rear opening 3 in the body of the garment extends from the neck of the body to the waist line 5 thereof.

At 6 is shown the trousers or bloomer portion of the garment which may be in the 50 nature of a downward continuation of the body 1 of the garment or which may be secured in any desired way thereto.

At 10 is shown the skirt portion of the garment which is secured to the body at 55 the waist band 5. The skirt portion 10 has its upper end at the rear of the garment in the nature of a flap 12 or "drop seat" portion. The trousers 6 at their rear upper end are secured to the flap portion 12 and 60 consequently may be dropped to uncover the body of the child when accessibility for sanitary purposes is required.

At the rear of the garment the "drop seat" portion 12 of the skirt and the upper 65 end of the trousers are reinforced by a band 13 which unites the same and which is adapted to be detachably secured over the waist band 5 of the garment by buttons 14 thereon which engage with button holes in 70 the band 13.

It will also be seen that a complete combination garment is provided which, by means of the central opening 3 in the body and the "drop seat" construction of the 75 trousers and skirt the garment may be readily placed on or removed from the child.

From the foregoing, it is obvious that my invention is not to be restricted to the exact embodiment shown but is broad enough 80 to cover all structures coming within the scope of the annexed claims.

What I claim is:

1. A garment having a body portion, a skirt portion extending therefrom, a trousers portion within the skirt portion and secured permanently and continuously thereto at the waist line, said skirt and trousers portion being permanently united at the rear of the garment to form a single movable 90 flap and means on said flap for detachably securing the same at the waist line of the garment.

2. A garment having a body portion, a central opening therein at the rear extending from the neck to the waist band, means for detachably closing said opening, a skirt portion secured to and depending from the body portion, a trousers portion secured within the skirt, said skirt and trousers portion being permanently united at the rear to form a single flap of double thickness and means on said flap for securing the same to the waist band of the garment.

3. A garment having a body portion, a central opening in the rear thereof extending from the neck of the garment to the waist band thereof, a trouser's portion secured to the body portion at the waist band and extending downwardly therefrom, a skirt portion secured to the body portion at the waist band and covering the trousers portion, said skirt and trousers portion being permanently united at the rear of the garment to form a single flap of double thickness, adapted to be raised or lowered 10 to and from the waist band and means for detachably securing said flap to the waist band.

Signed at the city, county and State of New York, this 10th day of May, 1921.

ESTHER BORGENICHT.
